J. B. WALSER.
WINDOW BALANCE.
APPLICATION FILED MAY 15, 1914.

1,131,097.

Patented Mar. 9, 1915.

UNITED STATES PATENT OFFICE.

JOHN B. WALSER, OF LEBANON, MISSOURI.

WINDOW-BALANCE.

1,131,097.

Specification of Letters Patent.

Patented Mar. 9, 1915.

Application filed May 15, 1914. Serial No. 838,789.

To all whom it may concern:

Be it known that I, JOHN B. WALSER, a citizen of the United States, residing at Lebanon, in the county of Laclede and State of Missouri, have invented a new and useful Window-Balance, of which the following is a specification.

The device forming the subject matter of this application is a window balance, and one object of the present invention is to provide a device of this type including a casing which may be connected with the window frame without mortising or cutting away the frame, the casing being provided with spring actuating means whereby the sash may be balanced.

It is within the scope of the invention to provide mechanism for actuating and controlling the rotatable element with which a flexible member is assembled, the latter being connected with the sash.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows in front elevation, a window frame to which the present invention has been applied; Fig. 2 is a vertical longitudinal section of the casing and attendant parts; Fig. 3 is a transverse section of the structure shown in Fig. 2; Fig. 4 is an end elevation of the structure shown in Fig. 2; Fig. 5 is a fragmental horizontal section showing a modified form of the invention; Fig. 6 is a cross section on the line 6—6 of Fig. 5; Fig. 7 is a perspective of the winding crank.

In the accompanying drawings, the numeral 1 indicates the frame of a window, the same comprising styles 1^a. Sashes 2 are mounted to slide in the frame 1, all as usual and well understood.

In carrying out the invention there is provided a casing denoted generally by the numeral 3, the same being a box-like structure open at the top only. Extended transversely

of the casing 3 and located at the inner end thereof is an end wall comprising portions 4 and 4^a, spaced horizontally from each other. This detail will be understood best 60 when the elements 20 and 20^a in Fig. 5 are examined, although Fig. 5 shows a modified form of the invention. A long shaft 5 is journaled for rotation in the part 4 of one end wall and in the opposite end wall of the 65 casing, as will be understood from Fig. 2. A short shaft 6 is journaled in the part 4^a of one end wall and in the opposite end wall of the casing. The shafts 5 and 6 are provided with external, squared ends 7 adapted 70 to receive a winding crank 37 which is shown in Fig. 7. Pivoted to the casing 3 as shown at 9 are pawls 8 adapted to engage the squared ends of the shafts 5 and 6 to hold the same against rotation. A drum 14 is 75 journaled for rotation on the shaft 5 and a drum 14^a is journaled for rotation on the short shaft 6. Brake plates 10 are provided, each brake plate including a laterally extended foot 11 operatively connected with the 80 bottom of the casing 3 by means of a screw 12. The brake plates 10 are provided with openings which receive hubs 38 formed on the ends of the drums 14 and 14^a.

Located within each drum 14 and 14^a is a 85 flat coiled spring 16, one end of which is inserted into and held in a slot 15 formed in the corresponding shaft 5 or 6, the other end of each spring being secured as indicated at 17 to the corresponding drum. 90 Flexible elements 18 are trained around the drums 14 and 14^a and are secured to the sashes 2.

The operation of the structure is as follows:—The winding crank 37 is mounted 95 on the end 7 of the shaft 5 and the same is rotated, the pawl 8 of the shaft in question having been disengaged from the squared end 7 of the shaft, so as to make a rotation of the shaft possible. When the shaft 5 is 100 rotated, the spring 16 is put under tension and after the required tension has been secured, the pawl 8 is engaged with the squared end 7, as shown in Fig. 4. This operation may be carried out in connection 105 with the shaft 6 for the obvious purpose of controlling the tension of the spring 16 which is individual to the shaft 6. When the sashes are lowered, the flexible elements 18 will be reeled off the appropriate drums 110 and the springs 16 will be put under tension, the springs reacting to balance the sashes

and to aid in lifting the sashes. In order to adjust the operation of the device for sashes of different weights, the screws 12 are rotated, thus pulling the brake plates 10 downwardly, or pushing them upwardly, the brake plates coacting with the hubs 38 on the drums 14 and 14^a to impose a greater or less friction thereon.

In Figs. 5 and 6, a modified form of the invention shown, the casing being denoted by the numeral 19 and being provided with a removable end wall comprising the horizontally spaced portions 20 and 20^a hereinbefore alluded to incidentally. Studs 21 are mounted respectively upon the portions 20 and 20^a of the end wall, the studs 20 being held in place by means of securing elements 22 which may be screws. Shafts 23 and 24 are provided. The shaft 23 has fixed thereto a pulley 26 and the shaft 24 has fixed thereto a pulley 25. Ball bearings 27 may be used in connection with the studs 21 and the pulleys 25 and 26 if desired. The ends of the shafts 23 and 24 are journaled for rotation in collars 28. Each collar 28 has a squared end 28^a engaged by a pivoted pawl 28^b of the sort hereinbefore described. Springs 30 are connected at their outer ends with the collars 28, the inner ends of the springs 30 being connected with the pulleys 25 and 26, although it is obvious that if desired the springs 30 may be connected directly with the shafts 23. This is a mechanical detail requiring neither extended description or specific illustration. Each pulley 25—26 is equipped with an outstanding hub 31 received in an opening 32 formed in a brake plate 33 having a foot 34 controlled by a screw 35 in the manner hereinbefore set forth. Flexible elements 38 are connected with the peripheries of the pulleys 25 and 26, the flexible elements 38 being connected with the sashes as hereinbefore described.

The operation of the structure shown in Figs. 5 and 6 needs no specific description in view of what has been stated hereinbefore in connection with that form of the invention which appears in Fig. 2. It is to be noted, however, that in order to adjust the tension of the springs 30, the shafts 23 and 24 are not rotated, the desired tension being secured in the springs 30 by rotating the collars 28 through the medium of their squared ends 28^a, the crank 37 being applied thereto.

Two casings 3 ordinarily are used and

the same are secured in the upper angles of the window frame as shown in Fig. 1. No mortising or cutting of the frame therefore is necessary. Owing to the fact that the removable end wall of each casing is thickened, as shown most clearly in Fig. 5, this end wall acts as a reinforcement, tending to prevent injury to the casing when one sash is moved up and somewhat violently into contact with the casing.

Having thus described the invention, what is claimed is:—

1. In a device of the class described, a casing; a collar journaled in the casing and having a polygonal end; a pawl pivoted to the casing and adapted to engage the polygonal end of the collar; a shaft journaled at one end in the collar and provided at its other end with a pulley; means upon the casing for supporting the pulley for rotation; a flexible element trained about the pulley; and a spring secured at one end to the collar, the other end of the spring being secured to move with the shaft and the pulley.

2. In a window balance, a casing; a rotatable element journaled in the casing and provided with a polygonal key receiving end; a movable locking device on the casing and adapted to engage directly with the polygonal, key receiving portion of the rotatable element to hold the latter against rotation; a spring secured at one end to the rotatable element; a drum; means for connecting the drum with the other end of the spring; and a flexible sash-controlling member wound upon the drum.

3. In a device of the class described, a casing; a collar journaled in the casing; releasable means coöperating with the collar to hold the collar against rotation; means for rotating the collar; a shaft journaled at one end in the collar and provided at its other end with a pulley; means upon the casing for supporting the pulley for rotation; a flexible element trained about the pulley; and a spring secured at one end to the collar, the other end of the spring being secured to move with the shaft and the pulley.

In testimony that I claim the foregoing as my own, I have hereto affixed my signature in the presence of two witnesses.

JOHN B. WALSER.
